FIG. 3.

FIG. 4.

Charles L. Pendleton, INVENTOR
BY Loyall J. Miller, ATTORNEY

UNITED STATES PATENT OFFICE

CHARLES L. PENDLETON, OF WEWOKA, OKLAHOMA

TANK FLANGE

Application filed October 27, 1928. Serial No. 315,569.

My invention relates to improvements in tank flanges.

The objects of my invention are to provide a device of the class described which will be new, novel, efficient and of utility; that is simple, strong, durable and which will be lasting and will not easily get out of order; which will be applicable for use on both wood and metal tanks; which will be useful on all kinds of tanks; which will prevent oil and the like from oozing out from around the flange connection and leaking.

The devices in use at the present time for the purposes for which my invention is intended are not practical nor efficient; they permit oil or other liquid to seep out from around the connection to the tank or receptacle and run down the side of the tank; and thus in the case of oil gets gradually worse the longer such seepage continues. In case of use for water filled tanks, the seepage accentuates the rusting of the parts of the flange connection, and of the parts of the tank there surrounding, and either causes the leakage to increase, or encrusts the parts together so that they cannot be loosened without opening up a larger hole around the flange connection than is intended.

With my invention all of these objections are obviated.

With these and other objects in view, as will more fully appear my invention consists in the construction, novel features, and combination of parts hereinafter more fully described, pointed out in the claims hereto appended, and illustrated in the accompanying one-sheet drawings, of which,

Figure 1 is a sectional view of the flange shown attached to a wall; Fig. 2 is a perspective view of the cap holding plate showing bosses with perforations; Fig. 3 is a perspective view of the body of the flange showing the spool neck integral therewith; Fig. 4 is a perspective view of a washer; Fig. 5 is an

elevational view of a tank showing the application of my device thereon.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is understood that the drawings are to be interpreted as being illustrative and not restrictive.

One embodiment of my invention is shown as follows: The spool necked body 1 of said flange is preferably circular in form at its base and has a roughed or corrugated upper surface 2 for rigidly holding a gasket 3 against the inside surface of a tank wall 4; said body has a square cornered portion 5 adjacent its center adapted to fit into a square opening 6 in said tank wall for preventing the turning of said flange. Above said square shouldered portion I provide a hollow cylindrical spool 7 having a rectangularly shaped head 8 and having a bore 9 therewithin extending from its upper top surface to the lower surface of said base of said flange 1 and having threads 10 throughout for the introduction therein of a pipe or hose 11. It will be understood that rubber fiber or other suitable gaskets may be used in connection with this flange. I also provide washers 12 having a perforation 13 in its center. This washer 12 is adapted to fit over the spool-necked portion of said flange and to be seated on the outside of said tank wall 4 and for seating on its outer face side a plurality of set-screws 19 hereinafter described. It will be noted that the spool-necked portion extends beyond the surface of the top of said base portion of said flange. I also provide cap holding plate 14 having a plurality of bosses 15 surrounding perforations 17 therethrough. These bosses and perforations may be increased in

number as desired owing to the largeness and the strength resisting quality required of the flange. Said cap holding plate has a rectangularly shaped opening 17 in its central portion, the top portion of said rectangularly shaped opening 17 has recesses 18 on two of its opposite sides therein for seating the square shouldered portion of the head 8 therein to prevent the turning of said flange except when desired. I also provide set-screws 19 being threaded for threadedly inserting in perforations 16 through said bosses 15 and for seating at 20 on the top surface of said washers 12. The number of these set-screws will correspond to the number of bosses and perforations used in the respective flanges.

The application of my invention can be seen as applied on tank 22 in Fig. 5. It will be understood that when the flange is to be applied to a circularly formed tank such as is shown at 22 that the upper corrugated surface 2 of said flange 1 of the lower surface 21 of said washer 12 will preferably be made to conform with the inner and outer surfaces, respectively, of the wall of the tank 4. The device as shown in Fig. 1 is shown applied to the straight surface instead of the cylindrical surfaced tank. It will also be understood that my device can be applied to wooden as well as metallic tanks, either in the cylindrical form or in the square or rectangular forms.

It will be observed by those familiar with the art to which my invention pertains that upon the introducing of the base of the flange 1 from the inside surface of the tank the neck portion 7 will be inserted through square opening 6 through said wall 4 of said tank, and that a suitable gasket 3 will be introduced on the upper roughed or corrugated surface portion 2 of the base of said flange 1, and between it and the inside surface of the tank wall; that the square shouldered portion 5 will then rest in said square opening 6 through the wall of said tank, and washer 12 will be placed surrounding the spool 7 and against the outer surface of said wall 4; the cap holding plate 14 will then be placed surrounding said spool-necked portion 7 up against the under shoulder of the head 8. Before being tightened said holding plate will be given a quarter turn after the head 8 has been placed through the rectangularly shaped opening and two sides of said head 8 will then be seated in said recesses 18 thereby preventing the turning of said head 8 in said top plate 14 and thereby holding the device securely and rigidly in position. Set-screws 19 will then be introduced through the perforations 16 in said bosses 15 in said cap holding plate 14 and their lower ends seated as at 20 on the upper surface of washer 12. These screw-bolts or set-screws 19 will be then tightened and the

base of said flange 1 will be drawn tightly against gasket 3 which in turn will be drawn tightly against the inner surface of said tank. The cap holding plate will be tightly drawn against the shoulder below said head 8 and the washer 12 will be securely tightened against the outer surface of said wall 4. This will permit a connection with said pipe 11 or suitable outlet pipes as desired for draining said tank or tapping it for other purposes; and no part of the liquid within said tank will be permitted to touch any part of the flange when so installed except the inner surface of the base of said flange 1 and the threaded bore into which is introduced pipe 11 through spool neck 7.

Having thus described my invention what is claimed and desired to be secured by Letters Patent is:

1. A device of the class described, comprising a body having a base, one surface of said base being roughed for securely holding a gasket member against the wall of a receptacle, a hollow internally threaded cylindrical neck integral with said base, said neck having on one end integral therewith a square cornered portion extending outwardly from said base for fitting in a square opening in the wall of said receptacle, and having on its free end integral therewith a rectangularly shaped square cornered head, said neck having a washer there around for setting against said wall, a clamping plate encircling said neck and tightly seating under said head, said plate having a plurality of screw bolts seating on said washer and for rigidly clamping said washer and said base against said wall.

2. A device of the class described, comprising a base roughed on one side for holding a suitable gasket, having an integral hollow cylindrical neck interiorly threaded for fitting a similarly threaded pipe, and having outstanding square cornered shoulders surrounding the base of said neck and integral therewith for fitting a square opening in a tank, said neck having a rectangular head on its free end, a gasket fitted between said roughed side of the base and the wall of said tank, said neck having a washer for fitting the opposite side of said wall, and a clamping plate having a central rectangular opening, two of its opposite walls of said opening having recesses for receiving said head, said plate having screw-bolts adapted for seating on said washer, said plate, said screw bolts and said head securely holding said device on said tank wall.

3. In a tank flange, the combination with a hollow cylindrical interiorly threaded sleeve member having an integral base for fitting the inside of a tank wall and having an integral rectangular shoulder above said base for fitting within a similarly shaped hole in said tank wall, of an integral rectangular

head upon the free end of said sleeve, said sleeve of sufficient length to accommodate varying thicknesses of tank walls, a clamping plate around said sleeve, said plate countersunk to snugly receive the adjacent portion of said head, and an annular bearing plate around said sleeve for contacting the outside of said wall, said clamping plate having bolt means for clamping said base and said bearing plate rigidly against their respective sides of said wall.
